UNITED STATES PATENT OFFICE.

CORA BELLE WILLIAMS, OF MALVERN, IOWA.

CORSET.

1,215,601.

Specification of Letters Patent. Patented Feb. 13, 1917.

Application filed December 16, 1915. Serial No. 67,232.

To all whom it may concern:

Be it known that I, CORA BELLE WILLIAMS, a citizen of the United States, residing at Malvern, in the county of Mills 5 and State of Iowa, have invented a new and useful Corset, of which the following is a specification.

The device forming the subject matter of this application is a corset of that type 10 called for when persons having unusually large figures and pendulous abdomens are to be fitted, the corset herein disclosed being so constructed as to give some looseness about the waist, combined with proper support for the abdomen. It is intended to 15 provide a garment which shall reduce pressure on the back along the spine, give adequate provision for the flesh under the arms, and fit properly about the busts.

Another object of the invention is to 20 improve generally, a garment of this type, in structural features which will be made manifest as the description of the invention progresses.

With the above and other objects in view 25 which will appear as the description proceeds, the invention resides in the combination and arrangement of parts and in the details of construction hereinafter described and claimed, it being understood 30 that changes in the precise embodiment of the invention herein disclosed can be made within the scope of what is claimed, without departing from the spirit of the invention. 35

In the accompanying drawings:—

Figure 1 is a plan wherein the outside of the garment is shown;

Fig. 2 is a plan wherein the inside of 40 the garment appears;

Fig. 3 is a cross section on the line 3—3 of Fig. 2;

Fig. 4 is a cross section on the line 4—4 of Fig. 2;

Fig. 5 is a cross section on the line 5—5 of Fig. 2;

Fig. 6 is a cross section on the line 6—6 of Fig. 2, parts being omitted;

Fig. 7 is a cross section on the line 7—7 50 of Fig. 1.

The garment forming the subject matter of this application may be made out of any desired material and comprises a pair of back pieces 1 provided with plaits 2 extended the full length of the garment, the plaits being adapted to be slacked away

when an increase in the circumferential dimension is required. Intermediate the plaits 2 and the inner longitudinal edges of the back pieces 1, the back pieces are reinforced 60 by double, covered stays 3 extended the full length of the garment. The back pieces 1 are reinforced further by short stays 4 which terminate in spaced relation to the lower edge of the garment. The longitudinal edges of the back pieces 1 are united by an inelastic cord 5, threaded through the said back pieces and extended upwardly, the ends of the inelastic cord 5 being united in a knot 6, adjacent the top of the garment. 70 Threaded downwardly through the longitudinal edges of the back pieces 1 is an elastic cord 7, the lower ends of which may be united by a knot 8. This combination of elastic and inelastic cords, mounted as above 75 described, serves to shape the garment properly, and to give play where play is needed, it being possible to tighten up the garment at the back without crowding the flesh downwardly. The back pieces 1 carry, 80 adjacent their upper ends, and upon the interior of the garment, quilted pads 9 disposed on opposite sides of the spine. The pads 9 serve to fill in the concavity in the back of the wearer and to prevent undue 85 pressure along the spine.

Adjacent their lower ends and upon their remote edges, the back pieces 1 are concaved as shown at 10, and secured to the concaved edges 10 of the back pieces are hip pieces 11 provided in their lower edges and intermediate their ends with darts 12. The lower edges of upwardly tapering gores 14 are secured to the upper edges of the hip pieces 11, the rear edges of the gores 14 being attached to the edges of the back pieces 1. These gores 14 serve to give the required fullness under the arms, the gores 14 being reinforced by stays 15 which extend upwardly from the upper edges of the hip pieces 11 to points adjacent the upper edge of the garment. The lower edges of reversely curved shaping strips 16 are secured to the upper edges of the hip pieces 11, the rear edges of the strips 16 being secured to the gores 14. Stays 17 extend upwardly from the upper edges of the hip pieces 11, the stays 17 passing across the seams between the shaping strips 16 and the gores 14 and lying partially on the gores 14 and 110 the shaping strips 16. Downwardly converging front pieces 18 are provided, the

rear edges of the front pieces 18 being secured throughout their upper portions to the front edges of the shaping strips 16, the lower portions of the rear edges of the front 5 pieces 18 being secured to the forward edges of the hip pieces 11. The front pieces 18 are reinforced by short stays 19 and long stays 20, and in the front pieces are formed plaits 21 which may be slacked away for 10 adjustment. Secured to the front pieces 18 adjacent the seams between the front pieces and the shaping strips 16 are upright retaining strips 22 with which are assembled the ends of transverse, featherbone ribs 23, secured 15 to the front pieces 18 and extended to points adjacent the forward edges of the front pieces 18. These stays or ribs 23 preferably are fashioned from featherbone and serve to shape the garment properly above 20 the bust and to prevent wrinkling. The front pieces 18 are provided with short stays 19 and with long stays 20. In the front pieces 18 are formed plaits 21 adapted to be slacked away for adjustment.

25 The invention comprises a strip 25 and a strip 29, the strip 29 being secured to the longitudinal edge of one of the parts 18, the strip 25 being provided with longitudinal braces 24. A lacing cord 26 or any other 30 suitable means unites the strips 29 and 25. The strip 25 carries hooks 27, adapted to be engaged with eyes 28, on a strip 30 secured to the longitudinal, forward edge of the other front piece 18. The strips 29 and 35 30, which are secured, respectively, to the forward edges of the front pieces 18, extend below the lower ends of the front pieces. Bridged across between the lower ends of the strips 29 and 30 upon the one hand and 40 the outer edges of the hip pieces 11 are elastic strips 31 disposed transversely of the garment and adapted to yield under pressure, these strips 31, in combination with the parts 11 serving to draw the garment inwardly 45 about the hips and the abdomen and to shape the garment properly, and to permit the necessary yielding, when the wearer assumes a sitting posture.

Assembled with the lower end of the garment at suitable points, are hose supporters 50

32 of any desired type. The front portions of the garment, at its upper end, may be connected by draw strings 33.

Having thus described the invention, what is claimed is:—

55 1. In a device of the class described, a pair of back pieces the lower forward edges of which are concaved; means for uniting the back pieces; hip pieces the rear edges of which are secured to the concaved edges of the back pieces; reversely curved shaping strips secured at their lower ends to the upper edges of the hip pieces adjacent the outer corners thereof; upwardly converging gores interposed between the shaping strips 60 and the back pieces and having their lower ends secured to the upper edges of the hip pieces; front members secured to the forward edges of the shaping strips; reinforcing strips secured to the forward edges of 65 the front members and extended downwardly below the lower ends of the front members; and elastic elements disposed transversely of the garment and located below the lower ends of the front members, the 70 rear ends of the elastic elements being secured to the forward edges of the hip pieces, and the forward edges of the elastic elements being secured to the rear edges of the reinforcing strips; and means for uniting 75 the reinforcing strips detachably.

2. A garment of the class described, comprising a pair of back pieces; pads on the inner surfaces of the back pieces adjacent their inner edges and adjacent their upper 80 ends; an inelastic lacing cord threaded upwardly through the back pieces and having its ends secured adjacent the upper edge of the garment; and an elastic lacing cord threaded downwardly through the lower 85 portions of the back pieces and having its ends secured adjacent the lower edge of the garment.

In testimony that I claim the foregoing as my own, I have hereto affixed my signature 90 in the presence of two witnesses.

CORA BELLE WILLIAMS.
